UNITED STATES PATENT OFFICE.

JAMES G. CHAMBERS, OF MONTREAL, QUEBEC, CANADA.

COVER.

Application filed December 29, 1924. Serial No. 758,768.

To all whom it may concern:

Be it known that I, JAMES G. CHAMBERS, a citizen of the United States, residing at Montreal, in the Province of Quebec and Dominion of Canada, have invented new and useful Improvements in Covers, of which the following is a specification.

In using the telephone, it frequently occurs that one of the users desires advice from another person in a room which he does not desire the party on the other end of the line to hear. This may be awkwardly accomplished by placing one hand over the speaking tube of the telephone, but it is my purpose to produce a simple means whereby the mouth of the speaking tube can be automatically closed by the user of the telephone by simply moving a slidible element on the telephone receiver.

A further object is the provision of means for closing the speaking tube of a telephone which is practically automatic in operation and which may be readily attached to any ordinary type of telephones.

With the above broadly stated objects in view and others which will appear as the nature of the invention is better understood, reference is to be had to the drawings which accompany and which form part of this application.

In the drawings:—

Figure 1 is a perspective view of a telephone provided with the improvement.

Figure 2 is a fragmentary sectional view approximately on the line 2—2 of Figure 1.

Figure 3 is a sectional view approximately on the line 3—3 of Figure 2.

Figure 4 is a side elevation of the telephone receiver having the clamping element of my improvement thereon, the latter being in section.

Figure 5 is a perspective view of the clamping element.

Figure 6 is a face view looking toward the mouth of the speaking tube.

Figure 7 is a sectional view approximately on the line 7—7 of Figure 6.

In carrying out my invention I arrange in the mouth piece 1 of a telephone 2, two disks or diaphragms 3 and 4 respectively. Each of these disks is provided with circumferential series of apertures 5 respectively, and the said disks are centrally pivoted, as at 7. The apertures 5 of the respective disks are normally in alignment, and the disk 3 is

fixed while the disk 4 is revoluble on the said disk 3.

Fixed to the inner face of the disk 4 and extending through an opening in the side of the mouth piece 1 there is an arm 8. This arm is pivotally connected with a plunger rod 9 received in a suitable cylindrical casting 10 that is fixed by a bracket 11 on the mouth of the speaking tube. The plunger 9 is influenced by a spring 12 so that the arm 8 is brought into contact with one of the walls of the slot 13 through which the said arm passes, and whereby the apertures 5 in the diaphragms or disks are sustained in alignment.

The cylinder 10 has its outer end closed by a cap member to which is connected a flexible tube 14, and guided through this tube there is a flexible shaft 15. Preferably the shaft is in the nature of a bendable but strong light wire.

The telephone receiver is indicated by the numeral 16, and has arranged thereon a clamping member of a particular and peculiar formation. The clamping member is 80 illustrated in detail in Figure 5 of the drawings and as shown therein, the same comprises a bowl-shaped end portion 17 from which extends a straight arm 18 that terminates in a band 19. The band is integrally formed with a curved spring finger 20. The cup-shaped end of the clamping member is designed to be received over the inner bowl-shaped end of the receiver 16, the arm 18 extending longitudinally along one side 90 of the said receiver, the band being arranged around the receiver and the spring finger 20 disposed over and in contacting engagement with the mouth of the receiver. The cup-shaped end 17 is provided with an opening 21 for the cable 22 between the stand of the telephone and the receiver 16, and is likewise provided with another opening 23 formed at the end of a depression 24, the said depression extending centrally through 100 the arm 18 and merging into a slot or opening 25.

The end of the flexible tube 14 is secured in the opening 23, while the flexible shaft is directed through the depression or groove 24 and through the slot or opening 25 in the clamping member. The end of the shaft 15 is secured to a slidible thumb piece 26 that has a guide element 27 that passes through the opening 25 and has an inner 110

flanged portion which is guided on the arm, preferably in a depression that is arranged along the edges provided by the said opening 25. The thumb piece 26 is curved in cross section and has its outer end formed with a lip 28.

It will be apparent that the party holding the receiver 16 can place his thumb or any finger against the thumb piece and by moving the same longitudinally, will draw on the flexible shaft 15, causing the latter to influence the plunger rod 9 against the pressure of the spring 12 to swing the inner disk 4 to bring the openings 5 therein out 10 of alignment with the opening in the outer disk or diaphragm 3 so that the mouth piece of the telephone will be closed and so that the user can readily converse with persons in a room without the liability of the party 15 on the second end of the line listening in.

Having described the invention, I claim—

1. In combination with a telephone, of a means for closing the speaking tube thereof, comprising a fixed apertured disk in the mouth of the speaking tube, a second apertured disk pivotally secured to the fixed disk, an arm thereon extending through the side of the speaking tube, spring means influencing the arm in one direction to turn the last mentioned disk to bring the apertures thereof in alignment with the apertures of the fixed disk, and means secured on and operable from the receiver of the telephone for influencing the arm in a second direction to bring the apertures of the disks 20 out of alignment.

2. In combination with a telephone, of a means for closing the mouth of the speaking tube thereof, comprising a fixed apertured disk in the mouth of the said tube, a second apertured disk pivotally secured to the fixed disk, spring influenced means for sustaining the last mentioned disk in one position to sustain the apertures thereof in 25 registering alignment with the apertures in

the fixed disk, a flexible shaft movable to influence the revoluble disk to a second position to bring the apertures thereof out of register with the apertures of the fixed disk, a clamp on the telephone receiver through 30 which the flexible shaft is guided, and a thumb piece slidably mounted on the clamp and to which the end of the flexible shaft is connected.

3. In combination with a telephone, of a means for closing the mouth of the speaking tube thereof, comprising a fixed apertured disk in said mouth, a second apertured disk centrally pivoted to the fixed disk and having an arm passing through the side of the 35 mouth piece, a spring influenced plunger connected to the arm, a casing therefor supported on the speaking tube, a flexible shaft connected with the plunger, a flexible tube through which the shaft is guided, a clamp 40 for the receiver of the telephone to which the tube is connected and through which the flexible shaft is guided, and a slidably thumb piece on the clamp guided thereby and to which the end of the flexible shaft is connected.

4. A clamp for a telephone receiver designed to serve as a guide for operating means for closing the speaking tube of a telephone, said clamp comprising a member having a cup-shaped end to be arranged against the inner end of the receiver, an arm extending from the cup-shaped end grooved to receive an operating flexible shaft there-through and having an opening at the terminal of the groove, a ring formed on the free end of the arm to surround the receiver, an arched spring finger on the ring to engage the mouth of the receiver, a slidably plate guided through the opening in the arm 50 and to which the end of the shaft is secured, and said plate having an upturned end.

In testimony whereof I affix my signature.

JAMES G. CHAMBERS.
